(57) **CLAIM**

The ornamental design for an electronics package, as shown and described.

DESCRIPTION

FIG. 1 is a front, top and left side perspective view of an electronics package showing our my design;

FIG. 2 is a rear, top, and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front elevational view thereof; and,

FIG. 10 is a rear elevational view thereof.

The broken lines in the drawings showing portions of the electronics package are included for the purpose of illustrating environmental structure and form no part of the claimed design.
